(57) **CLAIM**

The ornamental design for a handle for vegetable carving knife, as shown and described.

DESCRIPTION

FIG. 1 is a perspective view of a handle for vegetable carving knife of the new design;

FIG. 2 is a front elevational view of the handle of FIG. 1;

FIG. 3 is a rear elevational view of the handle of FIG. 1;

FIG. 4 is a left side elevation view of the handle of FIG. 1;

FIG. 5 is a right side elevation view of the handle of FIG. 1;

FIG. 6 is a top plan view of the handle of FIG. 1;

FIG. 7 is a bottom plan view of the handle of FIG. 1; and,

FIG. 8 is a perspective view of the handle of FIG. 1 including a blade assembly shown in broken lines.

The portions of the Figures shown in broken lines are not part of the claimed design but are for illustration purposes only.

1 Claim, 7 Drawing Sheets
